VIRGIL W. BLANCHARD, OF BRIDPORT, VERMONT.

Letters Patent No. 60,676, dated January 1, 1867.

IMPROVEMENT IN HARVESTERS.

The Schedule referred to in these Letters Patent and making part of the same.

TO ALL WHOM IT MAY CONCERN:

Be it known that I, VIRGIL W. BLANCHARD, of Bridport, in the county of Addison, and State of Vermont, have invented a new and improved Harvester; and I do hereby declare that the following is a full, clear, and exact description thereof, which will enable those skilled in the art to make and use the same, reference being had to the accompanying drawings, forming part of this specification, in which—

Figure 1, sheet No. 1, is a side sectional view of my invention taken in the line $z z$, fig. 2.

Figure 2, a plan or top view of the same.

Figure 3, a section of a part pertaining to the same taken in the line $y y$, fig. 2.

Figure 4, sheet No. 2, a section of a portion of the same taken in the line $z z$, fig. 2.

Figure 5, a section of fig. 4 taken in the line $x' x'$.

Figure 6, a section of the machine taken in the line $y y$, fig. 2; and

Figure 7, a detached front view of the grain-discharging device pertaining to the same.

Similar letters of reference indicate corresponding parts.

This invention relates to a new and improved arrangement of gearing for varying the speed of the sickle as circumstances may require. It also relates to a new and useful improvement in applying the driver's seat to the machine, and in the application of springs to the machine, as hereinafter fully shown and described, whereby the draught and movement of the working parts are rendered more uniform than hitherto. The invention also relates to an improved manner of attaching the platform to the machine, whereby the former may be readily detached when necessary; and lastly, the invention consists in an improved grain-discharging device arranged to operate in the manner hereinafter set forth.

A represents the main frame of the machine, which is supported by two wheels B B', one of which, B, is firmly secured on the axle C, and the other, B', placed loosely upon it. On the axle C, near the wheel B', there is placed loosely a collar, D, (see fig. 4,) having toothed wheels E F permanently secured on its ends, one wheel, E, being larger in diameter than the other, F; and on the axle C there are also placed loosely the sliding parts $a a'$, of two clutches G G', said parts $a a'$ passing loosely within the collar D, and having a spiral spring, H, connected with them which has a tendency to keep the parts $a a'$ thrust outward to their fullest extent. The axle C is allowed to turn freely within the parts $a a'$ of the clutches G G', but the collar D is connected with said parts in such a manner that when the latter are turned the collar D and wheels E F will be turned with them, and the parts still allowed to slide on the axle within the collar without sliding the latter. The spiral springs H have a tendency to keep the parts $a a'$ in contact with the other parts $b b'$, comprising the clutches G G'. One of these parts, b, is attached to the wheel B', and the other, b', to the axle C, and these clutches, it will be seen, form a connection between the axle C and the collar D, so that the latter, when the machine is drawn forward, will be rotated, and consequently the wheels E F, the parts $a a'$, $b b'$, being provided with ratchet-shaped teeth, so that the collar D will not be turned backward under a retrograde movement of the machine. The wheels E F gear into pinions I J, which are placed loosely on a shaft, K, on the rear part of the main frame A, said shaft being parallel with the axle C. The pinions I J have each the parts $c c'$ of clutches L L' attached to them, the other parts $d d'$ of said clutches being at the ends of a slide, e, which is fitted on the shaft K in such a manner that it may slide freely but at all times turn with the shaft. The slide e is moved so as to engage with either pinion I J by means of a lever, L'', (see fig. 2,) and it will be seen that the shaft K may be rotated from the axle C through the medium of the wheel E and pinion I, or the wheel F and pinion J, by simply connecting the slide e with the pinion I or J. On the shaft K there are also placed loosely two toothed wheels M N, which have the parts $f f'$ of ratchet clutches O O', attached to them, the other parts, $g g'$, of said clutches being at the ends of a slide, h, placed on the shaft K in such a manner that it may slide freely and still turn with the shaft at all times; and by adjusting this slide, which is done through the medium of a lever, P, either wheel, M or N, may be connected with shaft K so as to turn with it. The wheel M is larger in diameter than the wheel N, and gears into a pinion, Q, on the rear part of a shaft, R, which drives the sickle. The wheel N gears into a similar but smaller pinion, Q', on shaft R, (see fig. 2.) On the front end of the shaft R there is a crank, S, from which the sickle T is driven by a pitman or connecting-rod, U.

From the above description it will be seen that the sickle T may be driven with different degrees of speed in

consequence of the gearing arranged as described; for instance, if the shaft K be rotated from the axle C through the medium of the wheel E and pinion I, the motion of shaft K will be more rapid than if it were rotated through the medium of wheel F and pinion J, and besides these two different speeds which may be given the shaft K, the driving shaft R may be rotated with two different speeds from the shaft K, as desired; hence the sickle T may be driven with four different degrees of speed, either rate of speed being used, as circumstances may require. The pitman or connecting-rod U is connected to the crank S, of the shaft R, as follows: On said crank there is fitted a box, V, composed of two parts i i, which are placed in a case, W, with India-rubber or other springs j j interposed between the parts i i and the sides of the case W, (see fig. 3) and through the lower part of this case W the pitman or connecting-rod U passes, and is secured by means of a nut, k, and a shoulder, l, on the pitman or connecting-rod, as shown clearly in fig. 3. By this arrangement the motion of the sickle is rendered uniform, and the jars and concussions attending a crank motion avoided. X represents the driver's seat, which is attached to a standard, Y, the lower end of the latter being secured to the main frame by a joint, m, which is at the front side of the standard. To the bottom or under side of the standard there is affixed a piece of India rubber, Z, which serves as a spring and gives a necessary degree of elasticity to the seat. This arrangement, it is believed, possesses superior advantages over the elastic seat supports now in use, as it is cheaper and less liable to get out of repair.

A $\times$, (see figs. 1 and 2,) represents the rear part of the draught pole, and B $\times$ the double-tree attached thereto by a bolt, n, which passes through an oblong slot, o, in the draught pole, and also through an eye in a bolt, p, which bolt p passes through a box, q, at the under side of the draught pole, said box having within it an India-rubber spring C $\times$, the front end of which bears against a stop, r, attached to the under side of the draught pole. The rear part of the bolt p works in a guide, s, and the front part works through the stop r; the spring C $\times$ and box q being loose or not attached to the draught pole or any fixture connected therewith. The spring C $\times$, under the draught movement, bears against the stop r and admits of the double-tree having a certain degree of spring or a yielding movement, whereby the draught movement is rendered more uniform than it otherwise would be, and the motion of the gearing rendered more constant during the passage of the machine over uneven surfaces of ground. The sickle T may be constructed in the usual manner, and therefore does not require a special description, and the same may be said of the finger bar D $\times$. The connection, however, of the finger bar to the main frame A of the machine constitutes an essential feature of the invention, as important results are obtained by it. This connection is as follows: E $\times$ is a curved bar, the inner end of which is slotted vertically and longitudinally, to receive a guide; F $\times$, which is attached to a bar on the main frame by a pivot bolt, t, and through the upper end of this guide F $\times$ a bolt, G $\times$, passes, one end of which is secured to the main frame by a screw, u, the guide being secured on the bolt by jam nuts v v. By adjusting these jam nuts on the bolt G $\times$, the guide F $\times$ may be varied in position so as to be vertical or more or less inclined. This will be fully understood by referring to fig. 1. The inner slotted end of the bar E $\times$ has a pin, w, passing horizontally through it, said pin also passing through a slot, a $\times$, in the guide F $\times$, (see fig. 6.) The upper end of the guide F $\times$ is provided with a projecting lip, b $\times$, which extends over one end of a short bar, H $\times$, the other end of which is connected by a hinge or joint, c $\times$, to the upper side of the bar E $\times$. In the under side of the bar H $\times$ there is inserted a piece of India rubber, d $\times$, and this rubber may be placed in a box fitted in the bar H $\times$, and a set-screw, e $\times$, passes into the bar by which the rubber d $\times$, which serves as a spring, may be adjusted higher or lower. This spring, d $\times$, rests upon the bar E $\times$, and serves to counterpoise the finger bar and sickle, and throwing the weight of the same upon the truck wheel in a shoe at the inner end of the finger bar, hereinafter described. The finger bar D $\times$ is secured to the outer end of the bar E $\times$ by a bolt, f $\times$, and a joint, g $\times$, shown clearly in fig. 6, and the outer end of the bar E $\times$ has a lip, h $\times$, projecting from its front edge at right angles, said lip being curved upward at its front end, and having a shoe, I $\times$, secured to it by a pivot bolt, i $\times$, (see figs. 1 and 2.) To the rear part and under side of the shoe I $\times$ there is secured an India-rubber spring, j $\times$, which may be adjusted higher or lower by a set-screw, k $\times$. This rubber spring serves to press the front end of the shoe downward, and cause a wheel, J $\times$, in the front end of said shoe, to bear upon the surface of the ground. This wheel, J $\times$, is the one referred to in the previous paragraph. To the rear side of the bar E $\times$ there are attached two vertical cleats, n $\times$ n $\times$, between which the front end of an arm, K $\times$, works, the front end of said arm having an oblong slot, o $\times$, in it, through which the cleats n $\times$ n $\times$ a horizontal pin, p $\times$, passes. The rear end of the arm K $\times$ is attached to the main frame A. The outer end of the bar E $\times$ is connected by a chain, q $\times$, to a segment, r $\times$, at one side of the main frame, said segment having a lever, L $\times$, attached, which is within convenient reach of the driver on his seat X. By this mode of attaching the finger bar to the main frame of the machine, the finger bar and sickle are allowed to conform perfectly to the inequalities of surface over which they may pass, and by removing the bolt f $\times$ the sickle may be raised up on end and made to rest against the main frame, the wheel J $\times$ sustaining it. The finger bar and sickle may also be raised temporarily by actuating the lever L $\times$, and the guards or fingers may be more or less elevated at their points by adjusting the jam nuts v v on the bolt G $\times$, and thereby regulating the position of the guide F $\times$. M $\times$ represents the grain platform, which is attached to the rear edge of the finger bar D $\times$, by a flexible connection s $\times$, which admits of the free self-adjusting movement of the finger bar. On the rear part of this platform there is secured a frame, N $\times$, on which the lower end of a vertical shaft, O $\times$, is stepped, the upper end of said shaft being forked, and serving as bearings for two horizontal shafts P $\times$ Q $\times$, placed one above the other, and allowed to slide freely in their bearings. The lower shaft P $\times$ has one end of a lever, R $\times$, connected to it, said lever having its fulcrum on the upper end of an upright S $\times$, and the opposite end of lever R $\times$ is connected by a pitman, T $\times$, with a crank U $\times$, which is on one end of a shaft, V $\times$, and is driven from the axle C by a toothed wheel W $\times$ on said axle, gearing into a pinion, t $\times$, on shaft V $\times$. The lower end of the vertical shaft O $\times$ has a spring, u $\times$, connected to it, and the lever R $\times$ is connected with shaft O $\times$ by means of a curved arm v $\times$. The lower shaft P $\times$ has a horizontal

blocks x^x x^x , having journals at their lower ends which work in suitable bearings y^x y^x , on the platform or bed. These blocks, x^x x^x , are connected by a spring or springs, a_1 , and are parallel with the platform or bed, and they have the rear ends of two chains X^x attached to them, the chain of one block extending over the shaft Q^x , and over the top of the other block and around a pulley z^x , and then extending forward to the front end of the shaft Q where it is attached, as shown at a^x . The chain of the other block has a similar but reverse connection, as shown clearly in fig. 2. Each block x^x is provided with pendent arms, Y^x , which extend down nearly to the platform M^x , as shown clearly in fig. 7, and the lower shaft, P^x , has a pin, b^x , projecting up from it, the lower end of said pin being connected with a spring c^x , on shaft P^x . The shaft Q^x , has a pin, d^x , passing transversely through it, and the under side of the upper shaft Q^x , has an oblong slot, e^x , made in it, which has two indentations, f^x g^x , into which the pin b^x catches, (see fig. 1.) When the pin b^x is in the indentations f^x the pendent arms Y^x are distended or forced apart, as shown in fig. 7, and in this position they are shoved forward to the front edge of the platform M^x , under the action of the lever R^x , and when said arms have nearly reached the extent of their forward movement the spring c^x , to which the pin b^x is attached, comes in contact with the front prong of the shaft O^x , and is thereby actuated by the shaft P^x so as to throw the pin b^x out of the indentations f^x , and the arms Y^x immediately close under the action of the springs a_1 of the blocks x^x , the upper shaft, Q^x , being forced back under the pull or draw of the chains X^x , and the pin b^x catching into the indentation g^x . The arms Y^x , in closing, grasp the cut grain on the platform and are drawn back with the grain between them under the reverse motion of the lever R^x , until the latter nearly reaches the termination of its backward movement when the shaft O^x is turned, owing to its connection with the lever R^x , so as to move the arms Y^x with their load off from the platform, and the shaft P^x being still shoved backward, the upper shaft, Q^x , being held by the pin d^x the chains X^x open the arms Y^x , and the grain is discharged, and the arms are held in an open state in consequence of the pin b^x catching into the indentation f^x , and are held open while being again forced forward to grasp the cut grain.

Having thus described my invention, what I claim as new, and desire to secure by Letters Patent, is—

1. The arrangement of the collar D , with the wheels E or F attached, or both the sliding parts a a' or their equivalents of the clutches G G' , and the spring H , or its equivalent, all placed on the axle C , to operate in connection with the pinions I or J or both, substantially as and for the purpose set forth.
2. The clutches G G' , L L' and O O' , when combined and arranged with sliding collars or sleeves, and with variable or differential gearing, substantially as and for the purpose specified.
3. The curved bar E^x , in combination with the adjustable guide F^x , arranged as shown for the purpose of elevating or depressing the front ends of the fingers or guards, as described.
4. The arm K^x , connected to the rear side of the curved bar E^x as shown, in combination with the adjustable guide F^x connected with the bar E^x , as shown, for the purpose specified.
5. The bar H^x , connected to the upper side of the bar E^x , by a hinge or joint e^x , and provided with India-rubber spring d^x , as shown, in combination with the ~~lip~~ on the adjustable guide F^x , substantially as and for the purpose described.
6. The grain-discharging device composed of the two shafts P^x Q^x , arms Y^x , arranged with the chains X^x , and pulleys Z^x , and operated automatically from the axle C or other suitable driving shaft, by the lever R^x , pin b^x , substantially in the manner as herein set forth.

VIRGIL W. BLANCHARD.
